(57) **CLAIM**

The ornamental design for a tire tread, as shown and described.

DESCRIPTION

FIG. 1 is a perspective view of a tire tread showing the new design.

FIG. 2 is a front elevation view thereof. The top and bottom views thereof are identical.

FIG. 3 is a rear elevation view thereof.

FIG. 4 is a left side view thereof. The right side view thereof is a mirror image of the left side view; and,
 FIG. 5 is a detail view thereof, of the segment of FIG. 2 between the lines labeled “5.”

In the drawings, the broken lines depict unclaimed portions of the tire tread. The dot and dashed lines represent a boundary between the claimed and the non-claimed portions and form no part of the claimed design.
